UNITED STATES PATENT OFFICE.

WILLIAM SMITH, OF PHILADELPHIA, PENNSYLVANIA, ASSIGNOR TO JOHN C. GRAHAM, OF SAME PLACE.

DESIGN FOR A FRINGE OR TASSEL BLOCK.

SPECIFICATION forming part of Design No. 15,419, dated September 16 1884.

Application filed July 7, 1884. Term of patent 14 years.

To all whom it may concern:

Be it known that I, WILLIAM SMITH, a citizen of the United States, and a resident of Philadelphia, Pennsylvania, have invented a new and original Design for a Fringe or Tassel Block, of which the following is a specification.

My design is fully shown in the accompanying drawings; and it consists of a block having a notched surface showing rows of pyramidal facets *a*, extending around the block, the facets of one row being at an angle the reverse of that of the adjoining rows.

Blocks of different shapes are shown by Figures 1, 2, 3, 4, and 5 of the drawings, but the essential characteristic of the design is preserved in all of these forms. Figs. 6 to 10 are diagrams representing the cross-sectional form

on the line *x-x* of the blocks shown, respectively, in Figs. 1 to 5.

Having thus described the design, what I claim, and desire to secure by Letters Patent, is —

The within-described design for a fringe or tassel block, said design consisting of a block having a notched surface showing rows of pyramidal facets *a*, reversely inclined, as shown and described.

In testimony whereof I have signed my name to this specification in the presence of two subscribing witnesses.

WM. SMITH.
